UNITED STATES PATENT OFFICE.

HARRY C. STUTZ, OF INDIANAPOLIS, INDIANA.

DESIGN FOR A RADIATOR-CAP.

57,741.

Specification for Design.

Patented Apr. 26, 1921.

Application filed October 9, 1920. Serial No. 415,919. Term of patent 14 years.

To all whom it may concern:

Be it known that I, HARRY C. STUTZ, a citizen of the United States, residing in the city of Indianapolis, county of Marion, and State of Indiana, have invented a new, original, and ornamental Design for a Radiator-Cap, of which the following is a specification, reference being had to the accompanying drawing, forming a part thereof.

Figure 1 is a side elevation of the radiator cap.

Fig. 2 is a plan view of the radiator cap showing my new design.

I claim:

The ornamental design for a radiator cap, as shown.

HARRY C. STUTZ.
